UNITED STATES PATENT OFFICE.

MILES R. HUTCHISON AND JOSEPH L. WILEY, OF SHARON, OHIO.

CHURN.

SPECIFICATION forming part of Letters Patent No. 249,359, dated November 8, 1881.

Application filed May 4, 1881. (No model.)

To all whom it may concern:

Be it known that we, MILES R. HUTCHISON and JOSEPH L. WILEY, both citizens of the United States, residents of Sharon, in the county of Noble and State of Ohio, have invented a new and valuable Improvement in Churns; and we do hereby declare that the following is a full, clear, and exact description of the construction and operation of the same, reference being had to the annexed drawings, making a part of this specification, and to the letters and figures of reference marked thereon.

Figure 1 of the drawings is a representation of a vertical sectional view of our improved churn. Fig. 2 is a cross-sectional view of the same, and Figs. 3, 4, and 5 are detail views. Fig. 6 is an enlarged detail.

This invention has relation to barrel-churns which are centrally pivoted and operate by vibration; and the invention consists in the construction and novel arrangement of parts, all as hereinafter shown and described.

In the accompanying drawings, the letter A designates a folding stand or support, having on the upper ends of its branches the journal-seats a, for the reception of the journals b of the barrel B, said journals extending from bracket-plates or bases which are secured to the sides of the barrel.

To the under side of the barrel are fastened the angular bracket-plates c, which are provided with squared holes d in their downturned ends, to receive the squared ends e of the spring branches or hangers C, to which the weight D is secured. This weight is made of inexpensive metal, and the hangers C have bent lower ends, which are embedded in the upper portion of the weight, the points at which they are embedded being some distance apart. The space between these hangers allows them full play without interference or danger of wrenching out of the weight. When the weight is to be connected to the barrel the hangers are pressed toward each other at their upper ends and sprung into engagement with the brackets e by their outwardly-turned ends e.

Any ordinary well-hooped keg or barrel may be employed for the churn-body. A rectangular opening is made in its upper portion for access to the interior, as shown in the drawings.

In the concave sides of the barrel-chamber

are fitted, by their curved edges g, the permanent side sections, D', of the middle transverse partition. The inner edges, z, of these side sections extend downward vertically from the sides of the opening in the top of the barrel, and are grooved in V form to receive the angular sides s of the middle section or slide, E. This partition is slotted for action on the milk as the barrel is vibrated, and the middle section is made removable to facilitate the removal of the butter, as well as to render the churn easily cleaned. The lower edge of the middle section or slide, E, is curved to fit the bottom of the barrel, as indicated at h.

F indicates the cover for the opening in the top of the barrel. This is sawed out of the barrel in forming the opening; and in order to fill the kerf made by the saw, and to keep the cover in shape and prevent warping, it is provided with a flanged metallic margin, k. A stud, l, is formed on this margin or frame k, which is designed to engage with a recess, r, in the edge of the opening of the barrel, and a button, m, is pivoted to the barrel on the opposite side of the cover, so that it can be fastened securely in place.

In order to provide the air-passage and at the same time to prevent splashing, two holes, v, are bored through the cover at a little distance from each other, and these holes are covered by the base or block w of the handle P, said base being recessed at a' to form a communication between the holes v and with the intermediate outer hole, b', which is made from the recess through the base w.

In order to operate the churn, a handle-crank, H, is provided.

Having described this invention, what we claim, and desire to secure by Letters Patent, is—

The curved cover F, having the metallic marginal frame k and stud l, in combination with the recess r in the edge of the barrel-opening, and the fastening m, substantially as specified.

In testimony that we claim the above we have hereunto subscribed our names in the presence of two witnesses.

MILES R. HUTCHISON.
JOSEPH L. WILEY.
